UNITED STATES PATENT OFFICE.

JAMES E. WHITE, OF CENTER, OKLAHOMA.

RAILROAD-TIES.

March 20, 1902.

Specification of Letters Patent. Patented June 30, 1914.

Application filed March 20, 1914. Serial No. 836,973.

To all whom it may concern:

Be it known that I, JAMES F. WHITE,
a citizen of the United States, residing at
Center, in the county of Pontotoc, State of
Oklahoma, have invented certain new and
useful Improvements in Railroad-Ties: and
I do hereby declare the following to be a
full, clear, and exact description of the in-
vention, such as will enable others skilled
in the art to which it appertains to make
and use the same.

This invention relates to railroad ties, and more particularly to the class of ties which are formed of metal and cement.

15. An object of the invention is to provide a tie wherein any movement after the same has been set in place in the road-bed will be practically prevented.

20 A further object of the invention is to provide a tie, the ultimate cost of which will be very little compared to its great efficiency.

A still further object is to provide a tie wherein the rail may be effectually clamped upon the same and any movement there-

25 after prevented.
With these and other objects in view my invention consists in the arrangement and combination of parts as herein set forth.

Referring to the drawing: Figure 1 is a perspective view of my device. Fig. 2 is a longitudinal section of the same. Fig. 3 is a view of the several parts thereof being separated. Fig. 4 is a transverse section showing the manner of securing the several parts together.

Referring to the drawing by reference characters wherein similar parts are indicated by similar characters, my device comprises a base plate 1 having secured to its upper side by welding for instance and extending longitudinally thereof a trough member 2 of a width less than the width of the base member. This trough member comprises upwardly extending sides 3, bottom member 4 and outwardly extending flanges 5 on the upper edges of the sides 3. Struck from the end of the bottom member 4 is a projection 6 which is bent upwardly to form an end member for the said trough. This trough is completely filled with cement 7 and to the upper side of said trough is secured a plate 8 of a width greater than the distance between the flange members 5. This plate is secured to the said flange members by bolts 9 extending through apertures 10 in the flange member and apertures 11 in

the plate member. From this construction it may be seen that I have provided a tie which will be extremely strong and by virtue of the width of the base plate 1 the same may be held securely in the road-bed after the material of the said bed has been piled upon the member 1.

In order that a rail may be securely attached to the tie, I have provided on the upper side of the plate 8 an angularly shaped flange 12 extending transversely of the said plate and a short distance from the said flange is formed a boss 13, that is at a distance great enough to allow the rail to be placed between the said boss and the said flange. This boss is internally threaded and inserted therein is a screw 14 having a threaded shank for engagement with the boss and a head 15 of such shape as to overhang the flange of a rail to secure the same to the tie. 75 76 77

When it is desired to attach a rail to this tie the screw 14 is withdrawn from the boss 13 and the said rail placed upon the tie so that the portion of the angular member 12 will overhang and engage the flange of the said rail. This member prevents movement of the rail in one direction. To prevent the rail from moving in the other direction the screw 14 is inserted in the boss so that the head thereof will overhang the flange on the opposite side of the rail. This screw is then tightened until said flange is securely clamped between it and the plate 8, thus the rail is absolutely held from movement either longitudinally or transversely of the tie.

From the foregoing it may be seen that I have provided a railroad tie which will be prevented from moving after being set in place, and means which will securely clamp a rail to the said tie.

I do not wish to be limited to the specific embodiment of my invention shown for it is obvious that numerous changes may be made without departing from the spirit of the invention.

What is claimed is:—

1. In a railroad tie, a flat base plate, a U-shaped trough of lesser width than and attached to the upper side of the said base plate, filling material within said trough, a plate secured to the upper side of the said trough and extending throughout its length, means on the said plate to securely attach a rail thereto, flanges formed on the upper edges of said trough and extending out- 105 110

wardly therefrom and means to secure said plate to said flanges.

2. A device of the class described, comprising a base plate, a trough secured to and extending longitudinally of the base plate, said trough comprising upwardly extending sides and ends, a filling material within said trough, flanges on said sides and extending outwardly therefrom, a plate extending across and secured to said flanges throughout their lengths.

3. In a railroad tie, a U-shaped trough, cement within said trough, means to attach

a rail thereto, a base plate of greater width than the width of the trough secured to the lower face thereof, said base being of a length equal to the length of the trough and having portions extending outwardly from the sides of the trough at angles thereto.

In testimony whereof, I affix my signature, in the presence of two witnesses.

JAMES F. WHITE.
